UNITED STATES PATENT OFFICE.

WILLIAM S. HADAWAY, JR., OF NEW ROCHELLE, NEW YORK.

IMMERSION-HEATER.

1,258,767.

Specification of Letters Patent. Patented Mar. 12, 1918.

Application filed January 28, 1913, Serial No. 744,725. Renewed August 6, 1915. Serial No. 44,120.

To all whom it may concern:

Be it known that I, WILLIAM S. HADAWAY, Jr., a citizen of the United States, residing at New Rochelle, in the county of Westchester and State of New York, have invented new and useful Improvements in Immersion-Heaters, of which the following is a full, clear, concise, and exact description, reference being had to the accompanying drawing, forming a part of this specification.

My invention relates to improvements in electric immersion heaters.

Attempts have been made heretofore to construct immersion heaters by inclosing a resistor in a water tight jacket or tube from which it is suitably insulated, and contracting the jacket about the resistor by drawing, bending or swaging the tube to cause it to bind the resistor tightly, thereby maintaining the walls of the tube in close thermal conducting relation therewith. In such constructions the resistor becomes substantially a permanent part of the heater as a whole and cannot be replaced if defects develop, without almost destroying the water tight casing, or doing great damage to the structure of which the heater forms a part, or to which it is attached. Furthermore, the resistors used heretofore have required special protection and the water tight jackets therefore have been designed with a view to reinforcing and protecting said resistors. In addition, heaters of different capacities have had to be specially constructed for the various purposes for which they were intended, and once constructed were rendered practically useless by the failure of any one of the several resistors of which they were composed.

One object of this invention is to provide an improved immersion heater.

Another object is to provide an immersion heater having a heater unit which is readily removable.

Another object is to provide an immersion heater having a plurality of heater units all of which are independently removable and interchangeable.

Another object is to provide an immersion heater having a heater unit which is reinforced mechanically so that the heater may be kept in stock and handled without special precautions and which may be readily posi-

tioned in and removed from the immersion heater without injury.

55

Another object is to provide an immersion heater having a heating unit which is mechanically and electrically complete in itself and requires no further insulation when it is inserted in the casing of the immersion 60 heater.

In the accompanying drawings I have illustrated a number of immersion heaters which embody the various features of my invention. Other forms may, of course, be 65 devised which fall within the scope of the invention.

Figure 1 is a sectional elevation of an immersion heater consisting of a single heating unit properly incased;

70

Fig. 2 is an elevation of a heating unit with parts broken away to disclose the construction;

Fig. 3 is an enlarged sectional elevation thereof;

75

Fig. 4 is a sectional elevation of a two unit heater;

Fig. 5 is an end elevation of said heater;

Fig. 6 is a sectional elevation of the casing of a three unit heater;

80

Fig. 7 is an end elevation thereof;

Fig. 8 is a sectional elevation of a four unit heater;

Fig. 9 is an end elevation thereof;

Fig. 10 is a sectional elevation of a six unit heater;

85

Fig. 11 is an end elevation thereof;

Fig. 12 is a sectional elevation of an eight unit heater;

90

Fig. 13 is an end elevation thereof;

Fig. 14 is a sectional elevation of a two unit heater of a different form than that previously referred to;

95

Fig. 15 is a sectional elevation of a four unit heater of modified construction;

98

Fig. 16 is a side elevation of the heating units;

Fig. 17 is a sectional elevation on the line 17-17 of Fig. 15, with the resistance units removed.

100

Fig. 18 is a sectional elevation on the line 18-18 of Fig. 15;

One of the main underlying structural features common to all of the figures described above is the provision of electric 105 heating units of standard size and construc-

tion, and suitable water tight containers or jackets therefor, said containers communicating with a common casing or head where more than one container is employed, within which head suitable connections are made to terminals adapted to connect the resistors to an external circuit.

In Fig. 1, a single container 1, is shown, within which fits a single heating unit. Said unit consists in the preferred form of a sheet metal channel 2 having flanges 3, which are bent over to embrace between themselves and the base of the channel a suitable resistor and the necessary insulation therefor. In the present construction said resistor consists of a thin flat slotted ribbon 4 which is preferably doubled over upon itself so that its opposite ends may be brought out and rolled over to form adjacent terminals 5. The adjacent folds of the ribbon are insulated from each other preferably by a strip or strips of sheet mica 6, said folds being further insulated from the inclosing walls of the metal channel by further strips of mica 7 and 8, as clearly shown in Fig. 2. A strip of metal 9 acts as a cover plate and is held in place by the bent over flanges 3. Although in the present instance the resistor ribbon is doubled over upon itself, it is apparent of course that two independent ribbons may be employed, electrically connected at one end, their other ends serving as terminals.

This sheet metal channel 2 serves to reinforce and stiffen the resistor whereby it may be readily slipped into the container 1. Furthermore the said channel serves to properly position the resistor with respect to its insulation and compresses the various layers into a very small space, whereby the metal of the channel is in close thermal relation with said resistor.

The upper end of the container 1 is enlarged to form a suitable head 10. This head is provided with a cap or closure 11, the latter being preferably integrally united thereto to form a water tight inclosure. Suitable circuit terminals 12 are carried by said closure 11, being electrically insulated therefrom by mica washers 13 and 14 arranged on opposite sides of an opening in the end of said closure, said terminals passing through said opening and being supported by the mica out of contact with said closure. The terminal extensions 5 of the resistor ribbon, are received within the terminal tubes 12 and are preferably silver soldered therein. In the manufacture of the container 1, a metallic tube of approximately the desired internal dimensions is constructed, said tube being then broached out by a suitable tool so as to insure a cross sectional area of standard dimensions, said cross section being just sufficient to permit one of the heating units to be slipped into

the container readily without binding. Said unit fits loosely enough to permit insertion and withdrawal thereof, while at the same time it is close enough to the wall of the container to insure rapid heat conduction thereto with but slight temperature drop or loss of heat potential. With a construction such as described the heating units may be made up in standard sizes and kept in stock, the metal channel affording ample protection to the resistor whereby no special precautions are required in handling or storing said units. Similarly the containers may be kept in stock and a heater such as shown in Fig. 1 may be readily assembled at any time in the manner previously described. Furthermore if the heating unit should develop defects for any reason, said unit may be readily replaced by simply removing the cap 11 and making the necessary substitution of a new unit. Said cap is preferably brazed or silver soldered to the enlarged head 10 of the container 1, and accordingly may be removed therefrom when desired. Heating units of this form are adapted for use as preheaters on automobiles or elsewhere, where it is desired to vaporize gasoline. They may also be used in many other ways.

The heater shown in Fig. 4 is made up of two containers 15, each of which is integrally united to a flanged cap 16, the latter being integrally united to and closing the end of a cylindrical head 17. The outer end of said head is closed by a cap having mica washers similar to those previously described said washers carrying circuit terminals, which are connected to the heating units received within the containers. In this figure the same reference characters have been employed as in Figs. 1 and 2 to indicate corresponding parts, and accordingly further description is unnecessary. It will be noted, however, that there are two containers, each of standard internal dimensions whereby either heating unit may be readily replaced if found defective without disturbing the other unit, or without substantial injury to the device as a whole. The elongated head 17 permits the heater to be immersed in a liquid in such position that the liquid to be heated is removed some distance from the circuit terminals. The heater may be used in any position of course, although it is intended more for use in a vertical or nearly vertical position.

The heater shown in Figs. 6 and 7 is made up of three containers 15 united to a common header in a manner similar to that previously described. A heater so constructed is of greater capacity of course than one having either one or two heating units of the same individual capacity.

In Figs. 8 to 12 inclusive, I have illustrated further forms of immersion heaters wherein 4, 6 and 8 units respectively are em-

ployed. The containers 15 in these figures are arranged radially instead of side by side and parallel and the capacity thereof of course increases with the number of units 5 employed.

In Fig. 14 I have illustrated a further form of immersion heater wherein the containers 15 instead of projecting from and beyond the head extend back toward the 10 terminals. Said containers project from a circular head 18 which is in open communication with an elongated tube 19 of reduced diameter, communicating with a second head 20, the latter having a cap carrying the circuit 15 terminals in a manner similar to that previously described.

In Figs. 15 to 18 inclusive I have shown a water heater wherein a plurality of containers 15 are supported by a metal washer 20 21, the latter being clamped between two rings 22 and 23, suitable gaskets 24 being interposed between said washer and said rings. The liquid to be heated enters through the lower opening 25 and passing 25 through the chamber 26, is heated prior to making its exit through the opening 27 in the cap 28. A drain cock 29 is also provided.

The ends of the resistor ribbons are brought out of the open ends of the containers 15 and are suitably clamped as shown in Figs. 16 and 18 to jumpers 30, whereby the circuit connections may be changed at will, the circuit terminals 31 being spaced apart a convenient distance to facilitate the 30 connecting thereto of conductors. The said terminals are suitably inclosed in a removable casing 32 as shown.

Immersion heaters such as described above are adapted for a wide range of use. For 40 example: they may be used to heat water or oil, to melt glue, paraffin or wax, to generate steam, to warm milk, or to use in sterilizers, etc.

With all of the above forms of device 45 described any heating unit may be replaced readily. Furthermore a heater of any desired capacity may be readily assembled by simply designing a suitable head to which the desired number of containers may be 50 secured.

Although in the various forms illustrated, I have shown nothing but straight containers, I do not limit myself to this construction, as it is apparent that both the container 55 and the unit may be curved to the same radius, and said unit thereafter slipped into said container in the same manner as if these elements were straight, the essential feature in regard to this phase of the invention being that the unit and its container 60 shall have a sliding fit whereby they may be readily assembled, and the unit may be readily replaced, if necessary.

It is to be understood of course that the 65 invention is not limited to the particular

embodiments thereof described above as various other forms may be devised which fall within the scope of the appended claims.

What I claim as new and desire to secure by Letters Patent of the United States is:— 70

1. An immersion heater comprising a portable, self-contained unitary structure consisting of a water tight, heat conducting jacket, a metal sheath having a sliding fit within said jacket and a resistor incased 75 within said sheath and insulated therefrom, said sheath, resistor and insulation being pressed firmly together to form a compact heating unit, whereby the heat is transferred from said resistor to the outer surface of 80 said jacket with a minimum drop of heat potential.

2. An immersion heater comprising a plurality of containers of the same internal dimensions, a suitable head with which the 85 open ends of said containers communicate, and a resistor unit fitting within each container, the entire structure being water tight.

3. In an immersion heater, a sheet metal container open at one end, a resistor unit 90 having a sliding fit within said container, a head communicating with the open end of said containers, circuit terminals carried by said head and insulated therefrom, and electrical connections between said circuit terminals and said unit. 95

4. An immersion heater comprising a heating unit, a water-tight inclosing casing therefor, a cap for one end of said casing, and circuit terminals carried by said cap, 100 said terminals being insulated therefrom and electrically connected to said heating unit.

5. An immersion heater comprising a heating unit and a water-tight jacket therefor 105 within which said unit has a sliding fit, said unit comprising a sheet metal channel, a cover plate held in place by the bent over flanges of said channel, a resistor held between said channel and said cover plate, and 110 insulation on opposite sides of said resistor.

6. An electric heater comprising a slotted ribbon doubled upon itself to bring its opposite ends adjacent to each other, insulation between said folds, a sheet metal 115 inclosure for stiffening said ribbon, insulation between said ribbon and said inclosure and a container closed at one end within which the above parts are located, said adjacent ribbon ends passing out through the other 120 end of said container.

7. In an immersion heater, a heating unit comprising a resistor, a carrier therefor, and means for insulating said resistor from said carrier, said resistor having connections 125 from its opposite ends to adjacent terminals located at one end thereof, and a water-tight inclosing jacket for said unit, said terminals being carried by one end of said jacket and insulated therefrom. 130

8. In an immersion heater, a header, circuit terminals carried thereby, a plurality of similar tubes communicating at one end with said header and closed at the opposite end, and a plurality of heating units each fitting within one of said tubes, each unit having a pair of terminals which are located within said header and electrically connected to said circuit terminals.
- 10 9. In a fluid heater, in combination, a thin tubular container of heat conducting material, a supporting element having an opening therein, said container being closed at one end and having its open end integrally united to said supporting element, whereby a water tight construction is pro-
- 15

vided, a thin compact metal incased heating unit having a cross section similar to that of said tubular container, whereby it may have a sliding fit within said container, with its outer walls in close heat conducting relation thereto and terminals for said heating unit located at one end thereof, to provide for circuit connections exterior to said container.

25

In witness whereof, I have hereunto subscribed my name in the presence of two witnesses.

WILLIAM S. HADAWAY, Jr.
